UNITED STATES PATENT OFFICE.

WILLIAM C. BAXTER, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR ROUNDING SOLES.

1,080,191.

Specification of Letters Patent.

Patented Dec. 2, 1913.

Application filed April 4, 1912. Serial No. 688,370.

To all whom it may concern:

Be it known that I, WILLIAM C. BAXTER, citizen of the United States, residing at Beverly, in the county of Essex and State 5 of Massachusetts, have invented certain new and useful Improvements in Machines for Rounding Soles; and I do hereby declare the following to be a full, clear, and exact description of the invention, such as will 10 enable others skilled in the art to which it appertains to make and use the same.

The present invention relates to machines for trimming or rounding soles after they have been incorporated in boots and shoes, 15 and more particularly to machines of this type which are employed for trimming the edge of the sole at the heel seat.

One object of the present invention is to provide an improved machine of this type 20 which trims the edge of the sole evenly and uniformly without marring or otherwise defacing the upper of the shoe or the projecting margin of the sole.

In addition to trimming the edge of the sole 25 at the heel seat, it is often desired to bevel the projecting margin of this portion of the sole. In this operation as generally performed, substantially the entire surface extending from the junction of the sole and 30 counter of the shoe to the edge of the sole is beveled or randed. As the width of the projecting margin varies with different styles and sizes of shoes, it is desirable to arrange the randing mechanism so that all soles 35 are randed uniformly without necessitating a separate adjustment of the randing knife.

A further object of the invention is to provide a mechanism for randing soles uniformly which does not require an adjustment 40 for operation upon extension edges of varying widths.

With the above objects in view, the several features of the invention consists in certain novel features of construction, combinations 45 and arrangements of parts hereinafter described and claimed, the advantages of which will be obvious to those skilled in the art from the following description.

In the accompanying drawings illustrating 50 the preferred form of the invention, Figure 1 represents a side elevation partly in section of a machine embodying the several features of the invention in their preferred form; Fig. 2 is a detail illustrat-

ing a partial front elevation of the machine 55 shown in Fig. 1; Fig. 3 is a detail showing a partial side elevation of the machine and illustrating the crease guide and upper feed wheel in section; and Fig. 4 is a view partially diagrammatic illustrating the relative 60 transverse positions of the randing knife and crease guide.

The machine shown in the illustrated embodiment of the invention comprises a stand 1 supporting a head 2 in which is journaled a drive shaft 3 carrying a tight pulley 4 and a loose pulley 5 thereon. A suitable belt shifter indicated at 7 is slidably mounted upon the head of the machine and serves to change the belt from the loose to the tight 65 pulley, or vice versa. The drive shaft 3 is operatively connected with a feed shaft 9 through a pair of intermeshing spur gears 10 and 11. A second feed shaft 12 is journaled in the frame of the machine above the 70 feed shaft 9 and is driven by intermeshing gears 13 and 14 mounted upon the shafts 9 and 12 respectively. The outer ends of the two shafts carry feed wheels indicated at 75 15 and 16 which engage and grip the edge 80 of the sole between them to feed the shoe. The feed wheels are separated to allow the shoe to be readily inserted in or withdrawn from the machine and this is accomplished by mounting the lower feed wheel in a slide 85 17 which is vertically movable in the head 2. The feed wheels are normally forced together by a spring 18 which loosely embraces the slide 17 and is interposed between a shoulder formed upon the slide and a stud 90 19 threadedly mounted in the head 2. The slide is connected through a treadle rod 19' to a treadle, not shown, which serves to depress the slide against the action of the spring and separate the feed wheels. In 95 order to limit the upward movement of the feed wheel 15, a knurled nut 20 is threadedly mounted upon the end of the slide below the stud 19 and may be adjusted to accurately determine the working position of the lower 100 feed wheel. With this construction and arrangement, it is obvious that both the compression of the spring 18 and the normal position of the feed wheel may be varied either independently or in unison. In order 105 to compensate for vertical movements of the slide 17, the feed wheel is secured upon the outer end of a short shaft 21 journaled in

the slide 17 and connected to the feed shaft 9 through an Oldham coupling indicated at 22.

In this type of machine, the shoe is guided during its movement past the trimming knife by a crease guide which presses against the shoe at the junction of the upper and sole, thus trimming the edge of the sole substantially concentric with the outline of the counter. In the present invention the edge of the sole is trimmed or rounded by a stationary knife 32 which is provided with a vertical cutting edge positioned between the upper and lower feed wheels and arranged to sever the sole along the line determined by a crease guide 33 which is rigidly supported upon the machine frame. The crease guide is fastened to the head 2 and projects down outside of the upper feed wheel and is provided with an outwardly turned lip 34 at its lower end arranged to engage in the crease formed by the junction of the counter and sole of the shoe. In order to vary the width of the extension edge formed by the trimming knife, this guide has provision for a transverse adjustment relative to the knife by means of a bolt and slot connection indicated at 35. The trimming knife 32 is supported obliquely in a knife holder 36 and is retained in the holder by a clamping bolt 37. The knife holder 36 is formed integral with a bracket 38 secured to the head 2 and having provision for a transverse adjustment, thus allowing the knife to be positioned accurately with relation to the co-operating feed wheels. The shoe is supported in the proper operative relation to the machine by a table 40 having an inclined face 41 which bears against the bottom of the shoe and retains the shoe in a position convenient to the operator. As indicated clearly in Figs. 1 and 3, this table has provision for angular adjustment by means of a curved guide-way 42 and a clamping bolt 43. This adjustment of the table varies the angle at which the sole is supported and enables the operator to trim the edge of the sole at any desired angle.

In the present invention the edge of the sole is gripped by each of the feed wheels 15 and 16 upon both sides of the line of cut made by the trimming knife in order to insure the proper presentation and feeding of the work to the knife. It is desirable to avoid indenting or otherwise marring the margin of the sole inside of the line of cut. To this end, the lower feed wheel is provided with a central annular groove dividing the periphery into two separate feeding surfaces, indicated at 45 and 46 respectively. These two surfaces virtually constitute a pair of feed wheels, the outer one indicated at 46, having a roughened periphery to support and guide the work without exerting

any substantial feeding action, and the inner one indicated at 45 having a series of coarse teeth to positively grip and feed the work outside of the line of cut. This construction provides a feed member which engages the sole with different degrees of feeding action at opposite sides of the line of cut. The upper feed wheel 16 is also divided by an annular groove into two separate feeding surfaces, indicated at 47 and 48 respectively. In the present invention, however, both surfaces of the upper wheel are provided with coarse teeth to positively grip and feed the work, the subsequent randing operation in which the marginal surface of the sole is beveled off removing any marks or indentations which are formed in the surface of the sole. It will be further noted that the trimming knife is received in the annular groove formed in the wheels, which enables the two wheels to be positioned in close proximity to the knife and one another, thus insuring a positive and accurate feeding action upon the work.

The upper margin of the sole is generally randed or beveled, and in the present invention this operation is performed jointly with the rounding operation by a fixed randing knife 50 which is positioned in the rear of the trimming knife and in line therewith. The randing knife is provided with a lip 51 which is arranged to enter the crease and operate as a combined guide for positioning the shoe and guard to prevent the randing knife from cutting or defacing the upper. It will be noted from an inspection of Fig. 2 that the crease guide 34 and the crease guide 51 are positioned contiguous to one another, thus allowing the shoe to be fed smoothly and evenly past the knives without liability of catching and marring the upper. The randing knife is rigidly connected to the top of the guard 33 and has provision for a vertical adjustment, and horizontal adjustments to and from the knife both in the line of feed and transversely of the line of feed. These various adjustments are secured by adjustably securing the knife in a slide 52, which in turn is adjustably secured to a bracket 54 fastened to the top of the guard 33. The knife has provision for a vertical adjustment in the bracket 52 and is retained in adjusted position by a clamp bolt 55, and the slide 52 has provision for a horizontal transverse adjustment relative to the bracket 54 and is clamped in adjusted position by a bolt 56. The bracket 54 is adjustable relative to the guard 33 to move the randing knife to and from the trimming knife in the line of feed and is retained in adjusted position by a clamp bolt 57. It will be noted that with this construction and arrangement the randing knife is adjusted with the crease guide 33, thus causing the beveled surface to al-

ways commence at the same distance from the counter of the shoe independently of any adjustment which is made to vary the width of the extension edge.

5 While it is preferred to employ the specific construction and arrangement of parts shown and described, it will be understood that this construction and arrangement is not essential except so far as specified in the 10 claims and may be changed or modified without departing from the broader features of the invention.

Having thus described the invention, what is claimed is:

15 1. A machine for trimming the soles of boots and shoes having, in combination, a trimming knife, a guide positioned adjacent to the knife for determining the line of cut made by the knife, and a pair of feed members 20 engaging the sole upon opposite sides of the knife with a greater degree of feeding action upon the outside of the line of cut than upon the inside, substantially as described.

25 2. A machine for trimming the soles of boots and shoes having, in combination, a trimming knife, a guide positioned adjacent to the knife for determining the line of cut made by the knife, a feed member 30 engaging the sole inside of the line of cut made by the knife and arranged to guide and feed the sole without entering into and marring the surface, and a feed member engaging the sole outside of the line of cut and arranged 35 to dig into and positively grip the sole to feed the same, substantially as described.

3. A machine for trimming the soles of boots and shoes having, in combination, a trimming knife, a guide positioned adjacent to the knife for determining the line of cut made by the knife, a pair of feed wheels 40 engaging the sole upon opposite sides of the knife inside and outside of the line of cut and provided respectively with a periphery and arranged to frictionally engage the sole and 45 with a series of coarse teeth to dig into and positively grip the sole, substantially as described.

4. A machine for trimming the soles of 50 boots and shoes having, in combination, a trimming knife, a guide for the shoe, and a pair of feed wheels positioned in close proximity to one another above and below the knife, each feed wheel having an annular groove formed in its periphery in 55 which the knife is received, substantially as described.

5. A machine for trimming the soles of 55 boots and shoes having, in combination, a 60 guide for the shoe, a plurality of pairs of

feed wheels engaging the top and bottom of the sole constructed and arranged to provide a recess between the wheels of each pair, and a trimming knife having its cutting edge positioned between the upper and lower feed 65 wheels and received in said recess, substantially as described.

6. A machine for trimming the soles of boots and shoes, having, in combination, a pair of upper and lower coöperating feed 70 wheels, a trimming knife positioned between the feed wheels, a crease guide having provision for a transverse adjustment relative to the trimming knife, and a randing knife mounted upon the crease guide and adjust- 75 able therewith, substantially as described.

7. A machine for trimming the soles of boots and shoes having, in combination, a pair of upper and lower coöperating feed 80 wheels, a trimming knife supported between 85 the feed wheels, a crease guide having provision for a transverse adjustment relative to the trimming knife, a randing knife mounted upon the crease guide, and having provision for adjustment relative to the 85 crease guide, substantially as described.

8. A machine for trimming the soles of boots and shoes having, in combination, a trimming knife, a pair of feed wheels arranged to engage the sole on opposite sides 90 of the line of cut above and below the trimming knife, and a stationary crease guide supported adjacent to the trimming knife and arranged to determine the line of cut made by the knife, substantially as de- 95 scribed.

9. A machine for trimming the soles of boots and shoes having, in combination, means for feeding the shoe, a crease guide, and a randing knife supported in close 100 proximity to the crease guide and having provision for adjustment to and from the guide both in the line of feed and transversely of the line of feed, substantially as described.

10. A machine for trimming the soles of boots and shoes having, in combination, means for feeding the shoe, a crease guide, and a randing knife supported in close proximity to the crease guide and having 110 provision for a vertical adjustment and horizontal adjustments to and from the knife both in the line of feed and transversely of the line of feed, substantially as described.
